(57) **CLAIM**

The ornamental design for a massaging seat cushion, as shown and described.

DESCRIPTION

FIG. 1 is a front perspective view of the massaging seat cushion showing my design.

FIG. 2 is a front view of the massaging seat cushion of FIG. 1.

FIG. 3 is a rear view of the massaging seat cushion of FIG. 1.

FIG. 4 is a right side view of the massaging seat cushion of FIG. 1.

FIG. 5 is a left side view of the massaging seat cushion of FIG. 1.

FIG. 6 is a top view of the massaging seat cushion of FIG. 1.

FIG. 7 is a bottom view of the massaging seat cushion of FIG. 1; and,

FIG. 8 is another front perspective view of the massaging seat cushion of FIG. 1.

The broken lines are for illustrative purposes only and form no part of the claimed design.
